EXTENSIBLE FLOWER STAND

Samuel P. Kelly, 806 Grand Ave.,
Fort Worth, Tex. 76106

Filed Aug. 28, 1970, Ser. No. 24,743

Term of patent 14 years

Int. Cl. D11—02
U.S. Cl. D35—3

FIG. 1

FIG. 3

FIG. 1 is a perspective view of an extensible flower stand showing my new design in its retracted position;

FIG. 2 is similar to FIG. 1, but shows the flower stand in its extended position; and

FIG. 3 is a top plan view.

I claim:

The ornamental design for an extensible flower stand, as shown and described.
